UNITED STATES PATENT OFFICE.

FRANK P. SCHULTZ, OF MILWAUKEE, WISCONSIN, ASSIGNOR OF ONE-HALF TO JOSEPH A. ENDISCH, OF SHEBOYGAN, WISCONSIN.

CHILD'S VEHICLE.

Application filed April 4, 1922. Serial No. 549,373.

To all whom it may concern:

Be it known that I, FRANK P. SCHULTZ, a citizen of the United States, and resident of Milwaukee, in the county of Milwaukee, 5 and State of Wisconsin, have invented certain new and useful Improvements in Children's Vehicles; and I do hereby declare that the following is a full, clear, and exact description thereof.

10 The invention relates to toys of a tricycle type having the appearance of an aeroplane.

It comprises a body simulating a plane in appearance and cut away centrally to permit the operator's feet to act on pedals for propelling the device, a steering wheel being conveniently located and adapted to turn the single rear wheel for steering purposes.

20 A primary object of the invention is the adapting of parts having the appearance of an aeroplane to a propulsive and steering mechanism, whereby a child's toy results that may be readily and conveniently operated. The arrangement is such that there is no danger of injury to the child from projecting parts, and the steering mechanism is conveniently disposed so that the device is at all times within perfect control. The structure, simulating an aeroplane, does not obstruct the vision of the occupant of the vehicle and the general appearance of the device is such as to make it highly attractive to children.

25 An object of the construction is provision of means whereby the toy may be steered by the moving of a single rear wheel on a vertical pivot. By a system of levers and links this wheel is rotatable by means of a steering wheel and the utilization of merely one wheel makes for simplicity of construction and 30 ease of manufacture.

40 An object of the structure is the provision of means for storing articles, the rear of the device being hollow and provided with a lid. This feature is attractive to children.

45 With the above and other objects in view, which will appear as the description proceeds, my invention resides in the novel construction, combination and arrangement of parts, substantially as hereinafter described 50 and more particularly defined by the appended and more particularly defined by the appended claim, it being understood that such herein disclosed invention may be made as come within the scope of the claim.

In the accompanying drawing, I have 55 illustrated one complete example of the physical embodiment of the present invention constructed according to the best mode I have so far devised for the practical application of the principles thereof, and in 60 which:

Figure 1 is a plan view of the novel toy.

Figure 2 is a longitudinal section thereof on the line 2—2 of Figure 1.

Figure 3 is a bottom plan.

Figure 4 is a detail of the steering mechanism, and

Figure 5 is a vertical section on the line 5—5 of Figure 3.

Longitudinal body member 10 is provided with a front frame member 11 supported thereby and upwardly extending therefrom, and a dash 12 rigid therewith and extending upwardly therefrom. A hood 13 having a shape, such as is common in aeroplanes, is extended over front frame member 11 and dash 12 and rigid with front frame member 11 is a boss 14 supporting a propeller 15 rotatable on a pivot 16 extending through the boss. Planes 17 and 18 70 extend transversely of the device and are made rigid with each other at their ends by spacers 19. Extending rearwardly from hood 13 are side members 20 rigid with body member 10 and continuous with a housing 21 having the general shape of the upper 75 part of a fuselage. The housing 21 has an opening therein adapted to be covered by a closure 22 pivoting on a hinge 23 and provided with a handle 24. Seat 25 extends 80 transverse of the vehicle and is continuous with back 26 which, together with housing 21, forms a complete receptacle in which the child may place toys or other articles.

Housing 21 terminates in a downwardly 95 directed wall 27 from which vanes 28 extend rearwardly in a horizontal plane, vane 29 extending upwardly therefrom in a vertical plane. Body member 10 is apertured to receive a journal 30, rigid with a shank 31, 100 the upward movement of which, with respect to body member 10, is limited by a collar 32 and the downward movement of which is limited by transverse pin 33 contacting with an apertured disc 34. Shank 31 is provided 105 with a fork 35 in which rear wheel 36 is mounted to rotate. Secured to shank 31 is an arm 37 having an opening therein to re-

ceive the shank and a screw 38 threaded for adjustment against the shaft. Arm 37 is pivoted at 39 to link 40 which at 41 is pivoted to bell crank lever 42 rotatable on pin 43 supported by body member 10. Bell crank lever 42 is pivoted at 44 to link 45, which at 46 is pivoted to arm 47 rigid with steering shaft 48 mounted to rotate in an opening in plate 49, which is bent and secured by screws 40 to dash 12.

The lower end of shaft 48 is rotatably mounted in support 51 secured by flange 52 to body member 10 and to plane 18. Steering wheel 53 is conveniently positioned for rotation by a driver sitting on seat 25, whose back may be supported by back 26 and who is enabled to see over plane 17. To plane 18 brackets 54 are secured in which shaft 55 is mounted to rotate being provided with deformations 56 receiving the apertured ends of links 57 on which are pedals 58 disposed immediately below opening 59 in body member 10. Obviously, on the rotation of the steering wheel to the right, the levers and links cooperating with wheel 36 rotate on journal 30 so that the vehicle travels to the right. Similarly, in reverse movement of steering wheel 53, a corresponding movement is imparted to the toy. The arm 47, link 45, and bell crank lever 42 have loose connections so that there is no impedance to the free rotation of shaft 48. The links 57 swing on arms 59', which at 60 are pivoted to supports 61 so that the movement of the pedals is operative to rotate shaft 55. Wheels 55' are rigid with shaft 55

so that the operation of pedals 58 propels the vehicle.

It will thus be apparent that a child on seat 25 will be enabled to conveniently operate the device, his range of vision being unobstructed, free movement being permitted his legs and reliable operation being insured. The steering mechanism is within ready control and the parts are such as to eliminate possibility of danger to an operator.

I claim:

In a toy of the class described, the combination of a body having the general appearance of an aeroplane, a pair of front wheels, a rear wheel, a fork for said rear wheel, a journal on said fork received in an opening in the bottom of said body, a collar limiting the upward movement of said journal in said opening, means for preventing the downward movement of said journal thru said opening, a rigid member secured below said collar, a link pivoted to said rigid member, a bell crank pivoted to the other end of said link, said bell crank being pivoted to the bottom of said body, a second link pivoted to the other arm of said bell crank, a rod pivoted to the end of said second link, a steering shaft rigid with said rod, a steering wheel for rotating said shaft, and means secured to said body for supplying a bearing for said shaft.

In testimony that I claim the foregoing I have hereunto set my hand at Milwaukee, in the county of Milwaukee and State of Wisconsin.

FRANK P. SCHULTZ.
